FIG. 3.

UNITED STATES PATENT OFFICE.

STEFANUS NIELSEN, OF BROOKLYN, NEW YORK.

TYPE-WRITER.

1,246,776.

Specification of Letters Patent.

Patented Nov. 13, 1917.

Application filed May 10, 1916, Serial No. 96,501. Renewed February 5, 1917. Serial No. 146,861.

To all whom it may concern:

Be it known that I, STEFANUS NIELSEN, a citizen of the United States, residing in the city of New York, borough of Brooklyn, county of Kings, and State of New York, have invented a certain new and useful Type-Writer, of which the following is a specification.

This invention is a typewriter, and the object of the invention is, more particularly, to improve typewriters of the class to which my co-pending application Serial Number 17,771, filed March 29, 1915, relates.

From a more specific standpoint, the objects of the invention may be generally stated as follows: First, to provide a construction which will reduce the number of working parts in order to save power in operating the machine; second, a better arrangement of the operating elements, and, third, the provision of means whereby any type bar may be re-operated either from its normally inoperative position or while in any intermediate position.

The invention relates more particularly to machines of the character wherein the type bars are moved to printing position by mechanically driven means controllable by the operator, and are returned to normal position, out of engagement with the platen, by further mechanical means independent of the operator. There has been an objection to machines of this character because of the fact that, if an operator were actuating the machine at high speed, the type bars might not be returned quickly enough for a subsequent operation, and no means was provided for allowing of the subsequent operation of any particular type bar until it had been reset to its initial, inoperative position. The present invention provides means which entirely overcomes this disadvantage and allows the machine to be operated as rapidly as the most skilled operator can actuate the same.

Features of the invention, other than those specified, will be apparent from the hereinafter detailed description taken in conjunction with the accompanying drawings.

In the accompanying drawings, I have illustrated different practical embodiments of the invention, but the constructions therein shown are to be understood as illustrative, only, and not as defining the limits of the invention.

Figure 1 is a vertical section through a typewriter embodying the present invention, said section being taken on the broken line X—X of Fig. 2.

Fig. 2 is a rear view of the machine, with certain parts broken away, or omitted, in the interest of clearness.

Fig. 3 is a perspective detail showing a part of a type bar action, the type bar being shown in normal or rest position.

Fig. 4 is a view similar to that of Fig. 3, but illustrating a slightly modified form of type bar action.

Figs. 5 and 6 are details showing different portions of the cycle of operation of the preferred form of type bar action.

Fig. 7 is a detail of one of the type bars of the machine, and the mechanism for operating the same, and

Fig. 8 is a detail perspective of one of the elements of the modified construction.

Referring to the drawings, the type bars are designated by the reference numeral 1. These bars are pivoted at 2 in slots 3 formed in a supporting segment 4. The type bars are mounted radially of the segment and are adapted, when actuated, to strike the platen 1^a at a common printing point 5, being mechanically driven to said printing point 85 by means of tension springs 6 in the manner clearly set forth in my co-pending application hereinbefore referred to.

Type bars 1 are held in their normal or rest positions against the tension of springs 6 by stop members 7 which are pivoted at 10 to brackets 11 mounted on a cross-beam 12, which, in turn, is supported by lugs 12^a formed on the frame of the machine.

13 designates the finger-keys which constitute the keyboard, and, in the preferred embodiment of the invention shown in Figs. 1, 2, 3, 5 and 6 of the drawings, each key 13 is provided with a stem, to the lower end of which is pivoted one arm of a bell-crank 14 mounted for pivotal movement on a pin 15. The other arm of bell-crank 14 is pivoted to a push-rod 16, the function of which push-rod is to actuate its co-operating stop member 7 in order to release the corresponding type bar 1 and allow the associated spring 6 to move said type bar to the printing point.

Each push rod 16 has a guide piece 18 which is mounted between rollers 19 journaled on brackets 20 secured to cross-beam 12. When any particular key 13 is de-

pressed, the corresponding push-rod 16 will oscillate its associated stop member 7 on its pivot 10 and release the type bar corresponding to the key actuated.

As shown in Fig. 3, the guide pieces 18 are mounted on push-rods 16 in such manner that said guide pieces have two inclined faces in engagement with rollers 19. Thus, when push-rod 16 is advanced, its rear end is raised by guide piece 18 and rollers 19. The parts are so associated that, when the rod is in its normally depressed position, it will engage with a forwardly extending finger 17 formed on stop 7, but, when the rod is raised during its advancing movement, it will be moved or elevated free from engagement with said finger 17. The arrangement is such that the push-rod will operate upon stop 7 to such extent as to release link 9 before the end of the rod is tripped from engagement with finger 17. A spring 21 cooperates with each stop 7 so that, as soon as the stop is free from engagement with the push-rod, spring 21 will return the stop to its normal position shown in Fig. 3. Thus, even though the finger-key 13 is held down by the operator, stop 7 may be returned to its initial position to lock the type bar, when the same is returned to its raised position, in a manner hereinafter to be described.

To allow link 9 to move back to a position to be locked by stop member 7, the forward end 22 of each stop member is pivoted, as at 23, to the main body of the stop, and said pivoted portion is normally held in alignment with the remainder of the stop by a spring 24. The back end of projection 8 is made beveled or sloping, so that, as link 9 is retracted, the pivoted end 22 of the stop rides over said beveled edge of projection 8 and, after passing the projection, is forced into a locking position by spring 24.

From the foregoing it will be manifest that, when any particular key is depressed, the corresponding push-rod 16 will be actuated to release the co-operating typebar and allow spring 6 to drive said typebar to the printing point. As stated, the typebar is adapted to be returned to its reset or rest position, with spring 6 under tension, by suitable mechanical means, preferably operating independently of the typist. In the preferred embodiment of the invention, the resetting mechanism consists of a plurality of resetting units, two of which are shown in Fig. 2 of the drawing. Each unit consists of two plates 28 connected by bars 27, which plates are secured to a shaft 29. The bars 27 are preferably provided with roller bearings or sectional sleeves 27^a. Each shaft 29 is supported tangentially to segment 4 in bearings 29^a 29^b (see Fig. 2) and is geared to a common shaft 30, which is supported in bearings 30^a and 30^b carried by a cross-beam

30^c, the latter of which forms a part of the frame of the machine. In operating the machine, rotation is imparted to shafts 29 through shaft 30, which forms the prime mover. Shaft 30 may be driven by a spring 70 drum 31 or by electricity in the manner shown in my aforesaid co-pending application.

While two resetting units are shown, it will be understood that any number might 75 be employed and that they may be driven in train through universal joint connections, it being understood that the main shaft of each particular unit would be mounted tangentially to segment 4.

80 The rearward ends of each link 9 are provided with hook-shaped portions 32 which are adapted to engage with bars 27 so that, as said bars are advanced by the rotation of shafts 29, such links 9 as are in engagement with said bars will be moved longitudinally thereby into a retracted position.

Geared to shaft 30, through gears 34 and 35, is an upstanding shaft 33 which carries a pinion 36 engaging a rack 37 fixed to 85 platen carriage 38, and with platen carriage 38 co-operates suitable escapement mechanism, not shown, by virtue of which step-by-step movement is imparted to the carriage. However, because of the rack and 95 pinion connection 37 36 operating through shaft 33, the operations of shaft 30 are checked or limited to such times as when the platen is moving. That is to say, when the platen carriage moves transversely of 100 the machine, the spring motor 31 is free to actuate the resetting units.

Under these conditions, if a key 13 is operated to release a type bar 1, thereby resulting in its movement to the printing 105 point, immediately succeeding said movement the platen will be advanced through its escapement mechanism and movement will be imparted to shafts 29. The organization of parts is such that, when any particular type bar is in printing position, the hook end of its link will be positioned in the path of one of the rods 27, with the result that, when shaft 29 is operated, the hook of the link will engage with one of the rods 27, 110 thereby retracting said link. The retracting of the link will draw the type bar back to the rest position, and, in so doing, place the co-operating spring 6 under tension. Moreover, as the link moves to its normal position, the pivoted end 22 of the associated stop 7 will engage with the co-operating projection 8 on said link, with the result that the link will be locked in such position as to retain the type bar in rest position, with its 115 spring 6 under tension. As shown, each resetting unit is provided with five bars 27, and, when this number of bars is used, the gearing between the parts is such that, as the platen advances one letter space, the unit 120 125 130

is advanced one-fifth of a complete rotation. Thus, bars 27 successively operate upon the links of the keys successively actuated. If more bars 27 were employed, the gearing 5 would be such as to advance one bar at a time to proper, operative position.

It will be manifest that some means should be provided to govern the pivotal movement of links 9, so that they will be 10 presented to bars 27 in such positions as to be readily actuated thereby, and removed from engagement with said bars as soon as the resetting operation of that particular type bar is completed. To this end, each 15 type bar is provided at its rear end with a laterally projecting pin 26 which rests upon a guide tongue 26^a, and each spring tongue 26^a is of sufficient length to extend beyond the termini of the travel of the pin 26. 20 Guide tongues 26^a form a part of a plate 41 fixedly mounted on a cross-beam 46, as shown in Fig. 1. Coöperating with tongues 26^a is a like number of spring tongues 27^b mounted at their forward ends on bent-up 25 portions 43 secured to a cross-bar 44. The forward ends of tongues 27^b are in spaced relation to the corresponding ends of tongues 26^a, while the rear ends of tongues 27^b rest lightly upon tongues 26^a near their 30 joining with plate 41, as shown in Fig. 3. Each pin 26 of one of the links 9 coöperates with one pair of tongues with which said pin engages, and the inclination or curvature of said tongues is such that the hook-shaped portion 32 of each link is presented 35 to the operating bars 27 in proper position, and, after the link has been retracted to the desired extent, said tongues cause the link to be disengaged from the actuating bar 27. 40 The manner of operation is clearly shown in Figs. 3, 5 and 6. Fig. 5 shows the positions of the parts when the type bar is at the printing point. At this time, link 9 is in its forward position and resting on the 45 lowest portion of guide tongue 26^a. The letter having been printed at the printing point, the platen advances, thereby allowing the spring motor to rotate shafts 29, with the result that one of the bars 27 engages 50 with the hook-shaped portion 32 at the end of link 9, last operated. Bar 27 advances, carrying with it link 9 and retracting said link to rest position, with spring 6 under tension. However, it will be noted from 55 Fig. 5 that, as the link is retracted, its pin 26 rides on guide tongue 26^a, which slopes upwardly. The result of this construction is such that, when the link has been retracted sufficiently far, the hook 32 of the 60 link will be disengaged from bar 27. Guide tongues 26^a and 27^b are so proportioned that this disengagement will occur as soon as pin 26 has passed under the free end of the co-operating spring tongue 27^b, simultaneously 65 with which the coöperating stop 7 will have

engaged with the projection 8 on the link and locked the link in retracted position. The positions of the parts at this time are as shown in Fig. 3, and they remain in such positions until the type bar is again released by its key 13, at which time pin 26 will ride idly up and over its spring tongue 27^b until approximately that time at which the type bar reaches the printing point, whereupon it will have traversed the length 75 of tongue 27^b and will fall into engagement with its tongue 26^a or into the initial position shown in Fig. 5.

Each and every type bar operates in the manner specified, being released by its 80 finger-key and actuated by its spring 6 to the printing point, after which it is returned to its rest position by one of the bars 27, to which its associated link is directed and subsequently removed by the coöperating 85 tongues 26^a and 27^b.

As heretofore stated, it may happen that, when one letter is operated twice in succession, if the second operation too closely follows the first, not sufficient time has 90 elapsed to allow of the resetting mechanism returning the type bar to its rest position before the second operation takes place. In this event, only one impression would be made, and this difficulty has long been recognized in power-driven typewriting machines. According to the present invention, however, means is provided whereby the waiting for the completion of the resetting operation is rendered unnecessary, thereby 95 greatly increasing the speed at which the machine may be operated. This means is embodied, in the preferred form, in a heel 25 formed on each stop 7, and so positioned as to underlie the lower edge of link 9. The 100 function of heel 25 is nothing more or less than to trip hook 32 of link 9 free and clear of bar 27 during the resetting operation, since, by the provision of means to accomplish this result, the type bar is rendered at 105 all times within the control of the operator. Assuming, therefore, that link 9, shown in Fig. 5, has been engaged by one of the bars 27 and partially retracted, it would be normally maintained in engagement with said 110 bar until the retracting operation was completed. However, if the typist is operating the machine at high speed and wishes to follow the preceding operation by another operation of the same key, stop 7 would be 115 oscillated, not to release projection 8, but to lift heel 25 into engagement with, and thereafter raise, link 9, with the result that hook 32 of said link is disengaged from bar 27 as shown in Fig. 6. Spring 6 will have 120 been placed under sufficient tension, and type bar 1 retracted to such extent, that, even at this point, the second printing operation will be performed with certainty and the proper impression made. 125

The mechanism described, therefore, places all of the type bars under the will of the operator at all times, irrespective of the resetting operation, and, accordingly, the machine can not fail to carry out the operations of the most skilled operator. To insure proper coöperation between heel 25 and link 9, irrespective of the particular portion or elevation of the spring tongue 26^a with 10 which it is in engagement, the lower edge of link 9 is preferably curved or shaped in such manner as to compensate for the difference in elevation of different positions. The lower edge of each link is so positioned that 15 during the operation of stop 7 in releasing the projection A, when the links are in normally retracted or rest positions, the heel 25 of the stop will not come into engagement with the lower edge of the link since 20 at such times engagement of the heel with the link is not only unnecessary, but would increase the work to actuate the stop. It is only during the resetting operation of any particular link that it is within the zone of 25 operation of heel 25.

Because of the fact that the type bars are pivoted on a segment and that the resetting bars 27 are tangential to said segment there is necessarily a slight difference of relation 30 between the pivotal point on the various type bars and the different points along the length of the bars 27 with which the respective links coöperate. In order to place the links 9 at all times during the resetting 35 operation under the control of the heel 25, the contour of the lower edge of each link is shaped so that that portion of the lower edge of the link which is in juxtaposition with heel 25 during any particular period 40 of the resetting operation will be positioned relative to said heel that when the heel is operated, it will impart to the link just sufficient movement to lift it free from the resetting bar 27. Thus, the link shown in 45 Fig. 7 is of slightly different contour than that shown in Figs. 1, 3, 4, 5, and 6.

Moreover, because of the fact that the type bars are pivoted for movement radially of the segment while the links 9 are mounted 50 perpendicular to the tangential bars 27, it will be manifest that only that link which coöperates with the bars 27 midway of the length thereof will lie in the same plane as its coöperating type bar. The links at either 55 side of this central link will lie in different planes of their respective type bars. In order to obtain proper pivotal action between the type bars and the links, those portions of the links which are pivoted to the type-bars 60 should lie in the same plane as the type-bars, and, accordingly, such links as are not in parallel relation with their coöperating type bars are twisted near their points of pivoting to bring the pivoted portion of the 65 links into parallel relation with said type

bars. Thus those portions of the links which are pivoted to the type bars are parallel thereto and form proper pivotal connection.

In Fig. 4 is shown a slightly modified 70 form of means, controlled by the finger-keys, for releasing the type bars from their set positions. In accordance with this modification, the key 13^a is provided with a stem 48, to the lower end of which is pivoted 75 a dog 49 normally maintained in alignment with stem 48 by a spring 49^a. 51 is a rock-shaft carrying a fixed arm 50 adapted to be engaged by dog 49. The construction thus far described is substantially the same 80 as that illustrated in my co-pending application referred to, the parts being so arranged that dog 49 will leave arm 50 after the key has been depressed to a certain extent, and thereby allow the shaft to return to its initial position after having been oscillated by the depression of the finger-key. Rock-shaft 51 carries at its rear end a stop 52 and a crank-arm 53, both of which are fixed on the shaft. Stop 52 is adapted to 85 engage with a projection 54, which is pivoted at 55 to link 56, which link corresponds to link 9 of the preferred construction. The spring 57 serves to hold projection 54 in a normal, extended position, because of its engagement with a movement-limiting member 58 secured to said projection.

When rock-shaft 51 is operated by the depressing of key 13^a, stop 52 is oscillated out of engagement with projection 54, with the 100 result that spring 6 forces the type bar 1 to the printing point. When the type bar is subsequently returned through the medium of the resetting mechanism hereinbefore described, projection 54 will be retracted 105 against the tension of its spring 57 and, in this retracted position, will pass by stop 52. As soon as it has passed stop 52, spring 57 will throw the projection outwardly into engagement with the back end of the stop, 110 and the parts will be locked in rest position.

It will be noted that, whenever shaft 51 is rocked, arm 53 will be moved in accordance therewith, and this arm is so positioned that its end will overhang one end 60 of a lever 115 61 which is pivoted, at 62, to a suitable support 63. The oscillation of rock-shaft 51 will thus serve to pivotally move lever 61, depressing end 60 and raising the opposite end. Said opposite end is formed to underlie the lower edge of link 56, and, as a result, the pivotal movement of said lever, in the manner specified, serves the same purpose as the operations of heel 25 in the preferred construction, viz., to release the link 120 125 from the resetting mechanism when the key is actuated before the resetting mechanism has completed the resetting operation. It thus appears that, in the construction described, the machine may be operated at 130

very high speed without in the least interfering with its efficiency or positiveness.

Two constructions by which the releasing of the type action from the resetting mechanism is accomplished have been shown, and, in like manner, various modifications might be illustrated with reference to the resetting mechanism. However, I have shown only one, which is illustrated in Fig. 8. In accordance with this modification, instead of having plates 28 with bars 27 extending between them, which bars are common to a plurality of type bar actions, each type bar action is released by a separate plate 58, having projections 59 corresponding to bars 27, it being understood that the various plates 58 are successively positioned on drive-shaft 29, to which movement is imparted as hereinbefore described. Thus, instead of having a plurality of bars 27 common to a plurality of type bar actions, each action has its own particular plate 58, having its resetting projection 59.

Having thus fully described the invention, what I claim as new, and desire to secure by Letters Patent, is:—

1. In a typewriter the combination of a plurality of type bars normally occupying retracted rest positions, mechanical means for moving said type bars to perform the printing operation, manually operable mechanism for controlling the operations of the type bars, means for the returning of type bars to their normal rest positions after printing operations, and means governed by the type bar controlling mechanism for rendering said type bars irresponsible to the operations of the re-setting means.

2. In a typewriter the combination of a plurality of type bars normally occupying retracted rest positions, springs for moving said type bars to perform the printing operation, manually operable mechanism for controlling the operations of the type bars, means for the returning of type bars to their normal rest positions after printing operations, and means governed by the type bar controlling mechanism for rendering said type bars irresponsible to the operations of the re-setting means.

3. In a typewriter the combination of a plurality of type bars normally occupying retracted rest positions, mechanical means for individually moving said type bars to perform the printing operation, manually operable mechanism for individually controlling the operations of the type bars, means for the returning of type bars to their normal rest positions after printing operations, and means governed by the type bar controlling mechanism for individually rendering said type bars irresponsible to the operations of the re-setting means.

4. In a typewriter the combination of a plurality of type bars normally occupying

retracted rest positions, springs for individually moving said type bars to perform the printing operation, manually operable mechanism for individually controlling the operations of the type bars, means for the returning of type bars to their normal rest positions after printing operations, and means governed by the type bar controlling mechanism for individually rendering said type bars irresponsible to the operations of the re-setting means.

5. In a typewriter the combination of a plurality of type bars normally occupying retracted rest positions, mechanical means for moving said type bars to perform the printing operation, manually operable mechanism for controlling the operations of the type bars, means for the returning of type bars to their normal rest positions after printing operations, and means governed by the type bar controlling mechanism for individually rendering said type bars irresponsible to the operations of the re-setting means.

6. In a typewriter the combination of a plurality of pivoted type bars, normally occupying retracted rest positions, links associated with said type bars, mechanical means for individually impelling the links in a direction to force the type bars to a common printing point, means coöperating with each link for maintaining the links in retracted positions, manually operable mechanism for individually releasing the links to allow of the printing operation, mechanical means coöperating with the links for retracting said links subsequent to the printing operation, and means for individually rendering the links irresponsible to the operations of the re-setting means.

7. In a typewriter the combination of a plurality of pivoted type bars normally occupying retracted rest positions, links associated with said type bars, mechanical means for individually impelling the links in a direction to force the type bars to a common printing point, means coöperating with each link for maintaining the links in retracted position, manually operable mechanism for individually releasing the links to allow of the printing operation, mechanical means coöperating with the links for retracting said links subsequent to the printing operation, means for guiding said links into engagement with the retracting means, and means for individually rendering the links irresponsible to the operations of the retracting means.

8. In a typewriter the combination of a plurality of pivoted type bars normally occupying retracted rest positions, links associated with said type bars, mechanical means for individually impelling the links in a direction to force the type bars to a common printing point, means coöperating with each

link for maintaining the links in retracted positions, manually operable mechanism for individually releasing the links to allow of the printing operation, mechanical means 5 coöperating with the links for retracting said links subsequent to the printing operation, and means controlled by the manually operable means for individually rendering the links irresponsible to the operations of 10 the retracting means.

9. In a typewriter the combination of a plurality of pivoted type bars normally occupying retracted rest positions, links associated with said type bars, springs for individually impelling the links in a direction to force the type bars to a common printing point, means coöperating with each link for maintaining the links in retracted positions with the springs under tension, manually operable mechanism for individually releasing the links to allow of the printing operation under the impulse of the springs, mechanical means coöperating with the links for retracting said links and again placing 25 the springs under tension subsequent to the printing operation, and means for individually rendering the links irresponsible to the operations of the retracting means.

10. In a typewriter the combination of a plurality of type bars normally occupying retracted rest positions, said type bars being pivoted on, and adapted for radial movement relative to, a segmental support, links associated with said type bars, springs for 35 individually impelling the links in a direction to force the type bars to a common printing point, means coöperating with each link for maintaining the links and type bars in retracted positions, manually operative 40 mechanism for individually releasing the links to allow of the printing operation, means arranged tangentially of the segmental support and coöperating with the links for retracting said links subsequently 45 to the printing operation, and means for individually rendering the links irresponsible to the operations of the retracting means.

11. In a typewriter the combination of a plurality of type bars normally occupying 50 retracted rest positions, said type bars being pivoted on, and adapted for radial movement relative to, a segmental support, links associated with said type bars, springs for individually impelling the links in a direction to force the type bars to a common printing point, means coöperating with each link for maintaining the links and type bars in retracted positions, manually operative 55 mechanism for individually releasing the links to allow of the printing operation, means arranged tangentially of the segmental support and coöperating with the links for retracting said links subsequently 60 to the printing operation, means for guiding 65 said links into engagement with the retract-

ing means, and means for individually rendering the links irresponsible to the operations of the retracting means.

12. In a typewriter the combination of a plurality of type bars normally occupying 70 retracted rest positions, said type bars being pivoted on, and adapted for radial movement relative to, a segmental support, links associated with said type bars, springs for individually impelling the links in a direction to force the type bars to a common printing point, means coöperating with each link for maintaining the links and type bars in retracted positions, manually operative 75 mechanism for individually releasing the links to allow of the printing operation, a driven shaft arranged tangentially of the segmental support, means mounted on said shaft and driven thereby for retracting said links subsequently to the printing operation, and means for individually rendering the links irresponsible to the operations of the retracting means.

13. In a typewriter the combination of a type bar, a spring coöperating with said 90 type bar for impelling it toward a printing point, a detent coöperating with the type bar for normally maintaining the bar in a retracted rest position with the spring under tension, a finger key, connections between 95 the finger key and the detent for releasing the type bar to allow its spring to move the bar to the printing point, means for returning the bar from the printing point to the normal rest position, and means associated 100 with the detent for rendering said type bar irresponsible to the operations of the re-setting means.

14. In a typewriter the combination of a type bar, a spring coöperating with said 105 type bar for impelling it toward a printing point, a detent coöperating with the type bar for normally maintaining the bar in a retracted rest position with the spring under tension, a finger key, connections between 110 the finger key and the detent for releasing the type bar to allow its spring to move the bar to the printing point, means for returning the bar from the printing point to the normal rest position, and means mounted on 115 the detent and movable therewith for rendering said type bar irresponsible to the operations of the re-setting means.

15. In a typewriter the combination of a type bar, a spring coöperating with said 120 type bar for impelling it toward a printing point, a detent coöperating with the type bar for normally maintaining the bar in a retracted rest position with the spring under tension, a finger key, connections between 125 the finger key and the detent for releasing the type bar to allow its spring to move the bar to the printing point, means for returning the bar from the printing point to the normal rest position, and means for 130

rendering said type bar irresponsive to the operations of the re-setting means at the will of the operator.

16. In a typewriter the combination of a plurality of type bars normally occupying retracted rest positions, mechanical means for moving said type bars to perform the printing operation, manually operable mechanism for controlling the operations of the type bars, means for returning the type bars to their normal rest positions after printing operations, and means for rendering said type bars irresponsive to the operations of the re-setting means at the will of the operator to allow of consecutive operations of any particular type before the completion of the intermediate re-setting operation.

17. In a typewriter the combination of a plurality of pivoted type bars normally occupying retracted rest positions, links associated with said type bars, mechanical means for individually impelling the links in a direction to force the type bars to a common printing point, means coöperating with each link for maintaining the links in retracted positions, manually operable mechanism for individually releasing the links to allow of the printing operation, mechanical means co-operating with the links for retracting said links subsequent to the printing operation, guide fingers for guiding the links into engagement with the retracting means, and means for individually rendering the links irresponsive to the operations of the retracting means.

18. In a typewriter the combination of a plurality of pivoted type bars normally occupying retracted rest positions, links associated with said type bars, mechanical means for individually impelling the links in a direction to force the type bars to a common printing point, means co-operating with each link for maintaining the links in retracted positions, manually operable mechanism for individually releasing the links to allow of the printing operation, projections on the links, mechanical means co-operating with the links for retracting said links subsequent to the printing operation, spring fingers coöperating with said projections for guiding the links into engagement with the retracting means, and means for individually rendering the links irresponsive to the operations of the retracting means.

19. In a typewriter the combination of a platen carriage adapted for intermittent movement, a type bar movable toward and away from said platen carriage, a spring for impelling the type bar toward the carriage, means for normally maintaining the type bar in a retracted position with a spring under tension, manually operable means for releasing the type bar to allow the spring to move the said type bar toward the platen carriage, means for resetting the type

bar to its normal position, means for actuating the re-setting means, and means associated with the carriage and coöperating with the actuating means for synchronizing the operations of the actuating means and the intermittent movements of the carriage.

20. In a typewriter the combination of a series of power operated type bars, means for normally maintaining said type bars in a restricted position, means for releasing said type bars, means for subsequently retracting them and means, operable at the will of the operator, for individually releasing the type bars from the retracting means during the retracting operation.

21. In a typewriter the combination of a platen carriage adapted for intermittent movement, a type bar movable toward and away from said platen carriage, a spring for impelling the type bar toward the carriage, means for normally maintaining the type bar in a retracted position with a spring under tension, manually operable means for releasing the type bar to allow the spring to move the said type bar toward the platen carriage, means for re-setting the type bar to its normal position, means for rendering the type bar irresponsive to the resetting means, means for actuating the re-setting means, and means associated with the carriage and coöperating with the actuating means for synchronizing the operations of the actuating means and intermittent movements of the carriage.

22. In a typewriter the combination of a platen carriage adapted for intermittent movement, a type bar movable toward and away from the platen carriage, means for guiding the type bar, means for returning the type bar to resetting position after operation, means for guiding the resetting means, and means associated with the carriage and coöperating with the actuating means for synchronizing the operations of the actuating means and the intermittent movements of the carriage.

23. In a typewriter, a plurality of type bars mounted on a segment, means for individually moving the type bars to a common printing point, means arranged tangentially of the segment for resetting the type bars after operation, and means for intermittently actuating the resetting means.

24. In a typewriter a plurality of type bars mounted for radial movement on the segment, means for moving said type bars individually to a common printing point, a shaft mounted tangentially of said segment, means mounted on a shaft for resetting the type bars after operation, and a power shaft geared to the tangential shaft for normally imparting rotation thereto.

25. In a typewriter a plurality of type bars mounted for radial movement on the segment, means for moving said type bars

individually to a common printing point, a shaft mounted tangentially of said segment, means mounted on a shaft for resetting the type bars after operation, and a power shaft 5 geared to the tangential shaft for normally imparting rotation thereto, in combination with a platen carriage adapted for intermittent movement and connections between the platen carriage and the power shaft for 10 synchronizing the movements of the platen carriage and power shaft.

26. A typewriter embodying a plurality of type bars mounted for pivotal movement radially of a segmental support, means for 15 moving said type bars to a common printing point, a link associated with each type bar, a shaft mounted tangentially of the segmental support, means mounted on the shaft for operating the links to reset the type 20 bars to normal position after operation, and means for guiding the links into engagement with the resetting means.

27. A typewriter embodying a plurality of type bars mounted for pivotal movement 25 radially of a segmental support, means for moving said type bars to a common printing point, a link associated with each type bar, a shaft mounted tangentially of the segmental support, means mounted on the shaft 30 for operating the links to reset the type bars to normal position after operation, and guide fingers for guiding the links into engagement with resetting means.

28. A typewriter embodying a plurality 35 of type bars mounted for pivotal movement radially of a segmental support, means for moving said type bars to a common printing point, a link associated with each type bar, a shaft mounted tangentially of the seg- 40 mental support, means mounted on the shaft for operating the links to reset the type bars to normal position after operation, and

guide fingers for guiding the links into engagement with resetting means, in combination with additional guide fingers for precluding engagement of the links with the 45 resetting means during the movement of any type bars to the printing point.

29. A typewriter embodying a plurality of type bars mounted for pivotal movement 50 radially of a segmental support, means for moving said type bars to a common printing point, a link associated with each type bar, a shaft mounted tangentially of the segmental support, means mounted on the shaft 55 for operating the links to reset the type bars to normal position after operation and means for guiding the links into engagement with the resetting means, in combination with means for precluding engagement of 60 the links with the resetting means during the movement of any type bar to the printing point.

30. A typewriter embodying a plurality of type bars mounted for pivotal movement 65 radially of a segmental support, means for moving said type bars to a common printing point, a link associated with each type bar, a trunnion on each link, a shaft mounted tangentially of the segmental support, 70 means mounted on the shaft for operating the links to reset the type bars to normal position after operation, means coöperating with the trunnions for guiding the links into engagement with the resetting means 75 when the type bars are at the printing point and means coöperating with said trunnions for precluding the links from engaging with the resetting means while the type bars are moving to the printing point. 80

In testimony whereof I have signed my name to this specification.

STEFANUS NIELSEN.
